UNITED STATES PATENT OFFICE.

JOHN S. RAPSON, OF ELKINS PARK, PENNSYLVANIA.

BOLT-CASING.

No. 836,463.

Specification of Letters Patent.

Patented Nov. 20, 1906.

Application filed March 29, 1906. Serial No. 308,633.

To all whom it may concern:

Be it known that I, JOHN S. RAPSON, of Elkins Park, county of Montgomery, and State of Pennsylvania, have invented an improvement in Bolt-Casings Made from Stamped Sheet Metal, of which the following is a specification.

My invention has reference to bolts; and it consists of certain improvements, which are fully set forth in the following specification and shown in the accompanying drawings, which form a part thereof.

The object of my invention is to provide an inexpensive construction of bolt-casing made from stamped sheet metal.

My invention consists of the body part or case carrying the bolt when made of stamped sheet-steel or other suitable metal and comprising a long flat base with ends turned upward and perforated, also having two smaller perforated portions stamped from the base and bent upward intermediate of the ends, combined with a slideable bolt extending through the perforations of the four upwardly-extending parts and having means arranged upon it between the intermediate perforated upturned parts to limit the movement of the bolt and hold it to the base-plate.

My invention further consists in providing the base-plate with one or more upward-turned flanges of less length than the distance between the intermediate perforated parts, which acts to lock the means on the bolt to prevent it moving out of its extreme positions.

My invention also comprehends details of construction, which, together with the features above set forth, will be better understood by reference to the drawings, in which—

Figure 1 is a perspective view of a bolt embodying my invention. Fig. 2 is a plan view of the same. Fig. 3 is a cross-section of the same on line 3-3, and Fig. 4 is a plan view of the base-plate before being bent into the shape it finally assumes.

The structure embodied in this invention comprises the bolt part and the keeper. The body or base A of the bolt part is a flat steel plate stamped into the shape shown in Fig. 4 and then having its parts B B C C D D bent upward at right angles to the plane of the base, as shown in Figs. 1, 2, and 3. The base is rectangular and of considerable length and has its ends B B perforated to re-

ceive the bolt E. Intermediate of these end parts B B are the two upwardly-turned perforated parts C C, which are of greatly less width than the base-plate A and also act as guides for the bolt E. The end parts B B are preferably the full width of the base A, whereas the parts C C are very much narrower, so as to leave body metal upon each side of said parts.

The parts D D are two parallel flanged portions stamped up from the base-plates A and are of less length than the distance between the parts C C, and, moreover, they are out of alinement with the apertures in the said parts C C, so that the bolt E will be arranged between them. The bolt E is provided with a laterally-extending handle F, by which the bolt may be shifted, and its shank is adapted to be received between the ends of the flanges D and the parts C, as shown, so as to lock the bolt in its extreme positions. By employing two of the flanges D the bolt may be used as a right or left handed bolt, as desired, and these flanges also act as a means of stiffening the base-plate in the direction of its length. The two sets of transverse parts B and C act to stiffen the base-plate transversely.

I represents screw-holes, which are placed in the base-plate near each end and between the parts B and C. The bolt E, extending, as it does, through the four bearing parts B C C B, also adds great strength to the stamped-sheet-metal base part to hold it against bending.

The keeper G may be made in any suitable manner. In the form shown it is made of a strip of sheet-steel bent upon itself to form a flange K and then again bent upon itself to form the plate part H, in which the oblong hole J for the bolt E is formed. The ends of the plate may be riveted together at L, as shown. The parts H and K are provided with screw-holes to secure the keeper to the door-frame. If desired, the flange K may be omitted.

It is evident that where the bolt part is not to be reversible one of the flanges D may be omitted. Likewise one of the end parts B may be omitted and the bolt E shortened; but I prefer to make the parts as shown, whereby the structure is reversible.

While I prefer the construction shown, I do not confine myself to the minor details, as these may be modified without departing from the spirit of my invention.

Having now described my invention, what

I claim as new, and desire to secure by Letters Patent, is—

1. A bolt structure consisting of a body of stamped sheet metal having a base provided with two perforated end parts and two intermediate perforated parts of less width than the base-plate, combined with a slidable bolt extending through the perforated end parts and intermediate perforated parts and provided with means between the two intermediate perforated parts to limit the movement of the bolt.
2. A bolt structure consisting of a body of stamped sheet metal having a base provided with two perforated end parts and two intermediate perforated parts of less width than the base-plate and also having a longitudinal flange D of shorter length than the distance between the intermediate perforated parts, combined with a slidable bolt extending through the perforated end parts and intermediate perforated parts and provided with means between the two intermediate perforated parts to limit the movement of the bolt and adapted to lock over the ends of the longitudinal flange D to lock the bolt in its extreme positions.
3. A bolt structure consisting of the base part A of sheet metal having a perforated end part B, two perforated parts C C of less width than the width of the base and two longitudinal flanges D D of less length than the dis-

tance between the parts C C and separated a distance greater than the diameter of the bolt, all of said parts B, C, C and D D being bent upward from and integral with the base part, combined with the bolt E extending through the parts B and C C and between the flanges D D and having a laterally-extending handle F adapted to lock between the ends of the flanges D and the respective parts C C, the said flanges D D enabling the bolt structure to be right or left handed.

4. A plate from which to form the body of the bolt structure consisting of a long plate having its ends provided with holes, two intermediate oppositely-directed U-shaped cuts to form parts C C which are also provided with holes, and two oppositely-directed U-shaped cuts to form longitudinal parts D D the latter cuts being intermediate of the parts C C and with their uncut sides at right angles to the uncut sides of the said parts C C.

5. A bolt structure having a keeper consisting of a strip of sheet metal bent upon itself to form a flange K and also bent upon itself to form a plate H at right angles to the flange and provided with a bolt-hole.

In testimony of which invention I hereunto set my hand.

JOHN S. RAPSON.
